US0D1002735S

(12) **United States Design Patent** (10) **Patent No.:** **US D1,002,735 S**
(45) **Date of Patent:** **** Oct. 24, 2023**

(54) **GAME CONTROLLER**

(71) Applicant: **Amazon Technologies, Inc.**, Seattle,
WA (US)

(72) Inventors: **Michael Edward James Paterson**,
Lafayette, CA (US); **Giles David**
Matthew McWilliam, San Francisco,
CA (US)

(73) Assignee: **Amazon Technologies, Inc.**, Seattle,
WA (US)

(**) Term: **15 Years**

(21) Appl. No.: **29/851,454**

(22) Filed: **Aug. 29, 2022**

Related U.S. Application Data

(62) Division of application No. 29/803,762, filed on Aug.
16, 2021, now Pat. No. Des. 966,418, which is a
division of application No. 29/694,648, filed on Jun.
12, 2019, now Pat. No. Des. 928,235.

(57) **CLAIM**

The ornamental design for a game controller, as shown and described.

DESCRIPTION

FIG. 1 is a top, right perspective view of a game controller;
FIG. 2 is a bottom, left perspective view thereof;
FIG. 3 is a top view thereof;
FIG. 4 is a bottom view thereof;
FIG. 5 is a left-side view thereof;
FIG. 6 is a right-side view thereof;
FIG. 7 is a front view thereof; and,
FIG. 8 is a back view thereof.

(Continued)

The dashed broken lines depict portions of the game controller that form no part of the claimed design.

1 Claim, 8 Drawing Sheets
